UNITED STATES PATENT OFFICE.

JOHN H. LAUTERMAN, OF COLORADO SPRINGS, COLORADO.

STOVEPIPE.

SPECIFICATION forming part of Letters Patent No. 692,865, dated February 11, 1902.

Application filed October 22, 1901. Serial No. 72,591. (No model.)

To all whom it may concern:

Be it known that I, JOHN H. LAUTERMAN, a citizen of the United States, residing at Colorado Springs, in the county of El Paso and State of Colorado, have invented new and useful Improvements in Stovepipes, of which the following is a specification.

My invention relates to improvements in stovepipes, and contemplates the provision of a stovepipe comprising sections adapted to be readily adjusted with respect to each other to increase or diminish the length of the pipe and facilitate the placing of the same in its operative position and a simple, compact, and reliable device through the medium of which the sections may be expeditiously fixed with reference to each other, and the pipe thereby secured in its adjusted position.

With the foregoing in mind the invention will be fully understood from the following description and claims when taken in conjunction with the annexed drawings, in which—

Figure 1 is a perspective view of my improved stovepipe; Fig. 2, an enlarged detail transverse section with some parts in elevation; Fig. 3, a section taken at right angles to Fig. 2 and in the plane indicated by the line 3 3 of the latter; Fig. 4, disconnected perspective views of the parts making up the clamp which I prefer to employ, and Fig. 5 an enlarged detail section illustrating a modification.

Similar letters of reference designate corresponding parts in all of the several views of the drawings, referring to which—

A is the female section, and B the male section, of my improved pipe. The female section is provided with a longitudinal offset or loop a, which by preference extends throughout its length, and the male section has a complementary longitudinal rib or radial projection b—i. e., a rib or radial projection adapted to rest and move in the offset of the female section. Said rib or radial projection b may be and preferably is formed by the seam of the male section, as shown; but I do not desire to be understood as confining myself to this construction, as the rib or projection might obviously be formed apart from and independent of the seam without departing from the scope of my invention. On the female section, at a point adjacent to the off-

set a thereof, is the preferred form of device C. This device is a clamp and comprises a body c, riveted or otherwise connected to the female section and having a groove d in its outer side and also having its inner end arranged to abut against one side of the offset a, a slide e, arranged in the groove d and having a lip f, adapted to engage the other side of the offset, and also having an aperture g, elongated or oblong in the direction of its width, and a cam h, disposed in the elongated aperture of the slide and carried by and interposed between a pintle i, journaled and secured in the body c, and a head or enlargement j, arranged above the slide. Said head or enlargement serves to retain the slide on the body and also for the connection of a handle k.

In the practical operation of my improvements when the handle k of the clamp is turned toward the offset a the lip f on slide e is moved in a direction away from the offset, and the male section B may then be readily adjusted lengthwise in the female section or said female section may be similarly adjusted on the male section until the pipe is of the proper length and in the position desired. When, however, the handle k is turned into the position shown in Figs. 1 and 2, the offset a and the rib or projection b therein will be tightly clamped between the lip f of slide e and the inner end of body c, and in consequence the sections A B will be securely fixed with respect to each other and held against casual movement.

It follows from the foregoing that my improved pipe may be adjusted as to length and placed in the position desired with great convenience and facility and when in such position may as readily be securely fixed against casual movement or displacement; also, that when it is desired to remove the pipe the same may be readily accomplished after the handle k of the clamp is moved into the position opposite to that illustrated.

While I prefer to employ the clamp shown and described because of its simplicity, compactness, and efficiency, I do not desire to be understood as confining myself to the same, as a clamp of any other suitable construction may be employed without departing from the scope of my claims.

My improvements are obviously susceptible of being used to advantage in smoke-stacks and all other smoke-conveyers and air-flues, and the term "pipe" as herein used 5 is intended to comprehend the same.

The term "pipe" as herein used is also intended to comprehend tubular chutes, such as employed in transferring grain from elevators to barges and ships, and for conveying 10 coal from wagons to the basements of buildings, as there are frequently places where it is necessary to either lengthen or shorten the chute. When it is necessary to make the 15 pipe-sections of metal too heavy to spring and permit of the offset of the female section being pinched on the rib of the male section, I contemplate providing the offset and rib with transverse apertures a^7 a^8 at intervals of their length, Fig. 5, and the slide e' of the 20 device with a stud a^9 on the inner side of its lip f' to enter coincident apertures a^7 a^8 of the offset and rib when the said lip of the slide is moved inwardly—this to securely fix the sections against movement with respect 25 to each other.

Having described my invention, what I claim, and desire to secure by Letters Patent, is—

1. In an adjustable pipe, the combination 30 of a male section having an exterior, longitudinal rib or projection, a female section having a longitudinal offset of **U** shape in cross-section receiving the rib or projection of the male section, and a device comprising 35 a body fixed on the outer side of the female section at one side of the offset thereof, and

a member adjustable on the body and having a portion disposed at the opposite side of the offset with reference to the body and provided with means for coacting with the offset and 40 rib and fixing the sections against movement with respect to each other.

2. In an adjustable pipe, a male pipe-section having an exterior, longitudinal projection, a female pipe-section of sheet metal having 45 an outwardly-extending, longitudinal offset of **U** shape in cross-section receiving the projection of the male section, and a clamp on the female pipe-section for pinching the offset thereof against the projection of the 50 male section and thereby fixing the sections with respect to each other.

3. In an adjustable pipe, the combination 55 of a male section having an exterior rib or projection, a female section having an offset receiving the rib or projection of the male section, and the device comprising the body fixed on the female section at one side of the offset, a slide having means for coacting with the offset and rib to fix the sections to each 60 other, and also having an oblong aperture, and a cam arranged in said aperture and interposed between and carried by a pintle journaled in the body, and a head or enlargement disposed above the slide.

In testimony whereof I have hereunto set my hand in presence of two subscribing witnesses.

JOHN H. LAUTERMAN.
